US00D818507S

(12) **United States Design Patent** (10) **Patent No.:** **US D818,507 S**
(45) **Date of Patent:** **** May 22, 2018**

(54) **REPLACEABLE TIP FOR A ROTATABLE CUTTING TOOL**

(71) Applicant: **Kennametal Inc.**, Latrobe, PA (US)

(72) Inventors: **Chad Swope**, Bedford, PA (US); **David S Rose**, Windber, PA (US)

(73) Assignee: **KENNAMETAL INC**, Latrobe, PA (US)

(**) Term: **15 Years**

(21) Appl. No.: **29/595,575**

(22) Filed: **Feb. 28, 2017**

(51) LOC (11) Cl. **15-09**

(52) U.S. Cl.

USPC **D15/139**

(58) **Field of Classification Search**

USPC D8/70; D15/131, 138, 139

CPC E21B 10/38; E21B 10/56

See application file for complete search history.

(74) *Attorney, Agent, or Firm* — Matthew S. Bedsole

(57) **CLAIM**

The ornamental design for a replaceable tip for a rotatable cutting tool, as shown and described.

DESCRIPTION

FIG. 1 illustrates a perspective view of the right side of the replaceable tip of the design in accordance with the present invention.

FIG. 2 illustrates a perspective view of the left side of the replaceable tip of FIG. 1.

FIG. 3 illustrates an isometric view of the right side of the replaceable tip of FIG. 1.

FIG. 4 illustrates an isometric view of the left side of the replaceable tip of FIG. 1.

FIG. 5 illustrates a right side view of the replaceable tip of FIG. 1.

FIG. 6 illustrates a left side view of the replaceable tip of FIG. 1.

FIG. 7 illustrates a front view of the replaceable tip of FIG. 1.

FIG. 8 illustrates rear view of the replaceable tip of FIG. 1.

FIG. 9 illustrates a top view of the replaceable tip of FIG. 1; and,

FIG. 10 illustrates a bottom view of the replaceable tip of FIG. 1.

1 Claim, 10 Drawing Sheets
